UNITED STATES PATENT OFFICE.

GEORGE C. STEVENS, OF SEATTLE, WASHINGTON.

AEROPLANE ATTACHMENT.

1,396,894.

Specification of Letters Patent. Patented Nov. 15, 1921.

Application filed October 13, 1920. Serial No. 416,608.

To all whom it may concern:

Be it known that I, GEORGE C. STEVENS, a citizen of the United States, and residing at Seattle, in the county of King and State of Washington, have invented certain new and useful Improvements in Aeroplane Attachments, of which the following is a specification.

The invention relates to an improvement in aeroplane attachments, particularly sea planes capable of alighting on and arising from the surface of the water.

Sea planes of this type are, as is well known, provided with two or more pontoons acting as floating supports for the sea plane. It is the object of the present invention to provide these pontoons, or one of them, with means for controlling an opening into the interior of said pontoon, whereby the pontoon may be permitted to fill with water when the sea plane is supported on the surface, and the aeroplane may carry said water filled pontoons over a remote locality and discharge the water from the pontoon over a desired area. The invention is particularly useful to members of the forestry guard, in which service aeroplanes and the like have been heretofore used to enable the guard to supervise a large territory, as with an available body of water, the guard has at command, a means whereby he may transport a considerable quantity of water to a small or starting fire, and so direct the discharge of the water as to aid in extinguishing the fire.

In the drawings:—

Figure 1 is a side elevation of a sea plane of one of the pontoons partly in section to illustrate the valve mounting.

Fig. 2 is an enlarged plan showing the valve rod support.

For the purposes of the present invention, one or more of the pontoons 1, forming part of the sea plane 2, and of usual hollow con-

struction, is formed, preferably in its bottom with an inlet opening 3. A valve 4 is arranged within the pontoon to control this opening, and said valve is adapted to be operated by a rod 5, which extends through an elongated opening 6 in the top of the pontoon and is pivotally supported adjacent said pontoon and top between ears 7 as more particularly shown in Fig. 2.

The rod 5 extends to a position convenient to the aviator, so that he may readily control the opening 3 at will.

In use having discovered a fire, the aviator may fly to a body of water and landing upon the same, permit the pontoon to fill or partially fill by obvious control of the valve 3. Then with the water filled pontoon, the sea plane will be caused to rest on the surface and fly at an appropriate altitude over the area on fire, when the valve 3 is operated to permit the discharge of the water from the pontoon onto the burning surface.

Obviously a number of such sea planes could by the volume of water discharged check or even put out a considerable fire, and to this extent the invention is a valuable addition to forest protection, and while particularly contemplated for such use is obviously capable and contemplated for any and all other uses to which it may be put.

I claim:

A sea plane having a pontoon formed with an opening in the bottom thereof, a lever pivoted in the top portion and having an end portion extending into the pontoon adjacent the bottom opening, the other end portion extending to a point adjacent the operator's seat, a valve member pivoted to the end of said lever within the pontoon and adapted to close the opening in the bottom thereof.

In testimony whereof I affix my signature.

GEORGE C. STEVENS.
